FREEZING TRAY WITH DRAINAGE TOP

Logan L. Mallard, Norfolk, Va.

Application December 4, 1941, Serial No. 421,647

3 Claims. (Cl. 62—108.5)

This invention relates to refrigeration, and particularly to an improved ice tray or mold for use in the freezing compartments or evaporators of domestic refrigerators.

A difficulty encountered in the removal of ice from trays for use has been the freezing of the ice blocks or cubes to one another at the top of the grid compartments. Frequently, ice trays are provided with grids which allow the water to overflow and form a solid cake of ice over the top of the grids. The average user of domestic refrigerators seldom fills the tray properly, so that oftentimes an excess is poured into the tray and overflows the grid partitions. Also, water or moisture sometimes drains into the tray from the inner walls of the evaporator or from an adjacent tray, or the water in the several freezing compartments may overflow due to expansion.

An object of the invention, therefore, is to provide an ice tray constructed in a manner such as to avoid the difficulties above noted. More specifically, the improved tray is provided with self-draining surfaces at the top edges of the grid compartments which will ensure drainage of surplus water from said edges irrespective of the quantity of water poured into the tray, so that there will be no ice formation joining the cubes above the grid partitions.

Another object is to provide a tray for freezing ice cubes having a gas expansion chamber in the base thereof such as disclosed in my copending applications Serial Numbers 290,479 and 421,641, filed August 16, 1939, and December 4, 1941, respectively, wherein the frozen ice cubes will be free from one another and may therefore be more readily dislodged from their respective grid compartments.

The foregoing and other objects and advantages will become apparent in view of the following description taken in conjunction with the drawing, wherein:

Fig. 1 is a perspective view of a tray in accordance with the invention;

Fig. 2 is a section taken on the line 2—2, Fig. 1; and,

Fig. 3 is a transverse vertical section taken through a tray of modified construction.

Referring to the drawing in detail and first to Figs. 1 and 2, the improved tray is generally indicated at 10 and comprises an outer shell 11 and an inner shell 12 formed with a series of grid compartments 13. These inner and outer shells may be formed of suitable material, such as sheet metal stampings and joined in sealed relation at 14 by welding or in any other suitable manner.

When the shells are thus joined, a chamber 15 is provided at the base of the grid compartments or individual molds 13 which may be charged with a suitable expandible gas in the manner indicated in my copending application Serial Number 290,479, filed August 16, 1939. When the tray is placed in a freezing compartment or evaporator, the gas contracts or condenses in volume, and when the tray is removed from its freezing compartment and subjected to room or atmospheric temperature, the gas expands and acts on the flexible bottoms 15' of the freezing compartments 13 and flexes the latter upwardly to eject the ice mass or blocks from the respective compartments.

The outer marginal or edge portion of the inner shell is preferably formed with a rounded downturned edge or bead 16 to insure drainage of water from said portion.

20 The respective freezing chambers or compartments 13 are formed by a series of partition walls 17, 18, 19 and 20 which are joined at their upper edges on a curved line, or are in effect "roof-shaped," as indicated at 21 so as to avoid the formation of any flat surfaces on which water may collect. The top edges of the grid partitions at the central area of the tray reach their highest peak at this point and slope gradually outwardly towards the sides and ends of the tray. In determining the height of the grid partitions, allowance should be made for expansion of water during the freezing process. Irrespective of how much water is poured into a tray, constructed in this manner, there will never be a film of water collecting over the tops of the partitions.

30 Fig. 3 shows a tray of single wall construction, or one wherein the outer shell 11 is eliminated. In this instance, the tray may consist of the inner shell only of Figs. 1 and 2 and parts thereof 35 which correspond to such inner shell are given like reference numerals with the exception that a prime has been added.

A tray of the type herein disclosed is of particular advantage for use with a gas expansion 45 ice ejecting or dislodging means and whereby the ice cubes or blocks may be automatically dislodged when the tray is removed from its freezing chamber and exposed to room or atmospheric temperature. In a tray of this type, the cubes 50 may not all be dislodged simultaneously by the force of the expanding gases, due to lack of uniformity in resistance encountered when the diaphragm pressure is applied, or for other causes, and if there is no ice bond between the respective 55 cubes, they are more easily dislodged.

It will be understood that the drawing and description are to be construed as illustrative and not as imparting limitations to the invention, the scope of the latter being defined by the appended claims.

What is claimed is:

1. An ice tray comprising an inner shell formed with transverse and longitudinal partitions defining a series of grid compartments, the top edges of said partitions having rounded surfaces and lying above the level of the surrounding walls of the tray to thereby automatically drain water from said top walls and avoid formation of an ice bond between the ice cubes of the respective grid compartments, and an outer shell spaced from 15 said inner shell to provide an expansion chamber adapted to contain an expansible gas to effect automatic dislodgement of the ice cubes when the tray is removed from a freezing chamber and exposed to room or atmospheric temperature.
2. An ice tray comprising side and end walls defining a main compartment, partitions extending transversely and longitudinally of said main compartment and dividing the latter into a plurality of individual grid compartments, said par- 20 25

titions at their upper edges being formed by walls having rounded contours, the rounded tops of said walls reaching a peak along the longitudinal center line of the tray and intermediately opposite ends thereof to thereby cause drainage of fluid outwardly toward the sides and ends of the tray when the grid compartments are filled preparatory to freezing of the fluid therein.

3. An ice tray comprising side and end walls defining a main compartment, partitions extending transversely and longitudinally of said main compartment and dividing the latter into a plurality of individual grid compartments, said partitions at their upper edges being formed by peaked walls having rounded contours arranged to drain outwardly towards the sides and ends of the tray, said main compartment having its bottom wall spaced from the bottom walls of the individual grid compartments to provide an expansion chamber adapted to contain an expansible gas to effect automatic dislodgment of ice cubes when the tray is removed from a freezing chamber and exposed to room or atmospheric temperature.
